UNITED STATES PATENT OFFICE.

MAX RUMPF AND WILLIAM E. NIMZ, OF CHICAGO, ILLINOIS.

SELF-INKING STAMP.

1,356,172.

Specification of Letters Patent. Patented Oct. 19, 1920.

Application filed February 2, 1920. Serial No. 355,877.

To all whom it may concern:

Be it known that we, MAX RUMPF and WILLIAM E. NIMZ, citizens of the United States, residing at Chicago, in the county of Cook and State of Illinois, have invented certain new and useful Improvements in Self-Inking Stamps, of which the following is a specification, reference being had to the accompanying drawings, forming a part thereof.

The purpose of this invention is to provide an improved self-inking stamp, adapted for hand operation and for carrying a multiplicity of detachable and interchangeable stamps, and without regard to the multiplicity of stamps or means for carrying such multiplicity, to provide an improved mechanism for inking the stamp in the initial portion of its descent and withdrawing the inking pad out of the path of descent without widening or dragging motion upon the stamp. It consists in the elements and features of construction shown and described as indicated in the claims.

25 In the drawings—

Figure 1 is a front elevation of a stamp embodying this invention.

Fig. 2 is a right-hand end elevation of the same.

30 Fig. 3 is a sectional detail side elevation of certain parts concerned in the movements.

Fig. 4 is a rear side elevation of the entire structure.

35 Fig. 5 is a detail section at the line, 5—5, on Fig. 4.

Figs. 6 and 7 are similar sections showing different positions of the parts.

Fig. 8 is an end view of the rotor stamp carrier having a piece broken out to disclose interior parts.

Fig. 9 is a section at the line, 9—9, on Fig. 8.

Fig. 10 is a section at the line 10—10, on 45 Fig. 9.

The structure shown in the drawings comprises a frame or supporting structure consisting of end standards, 1, 1, and cross-heads, 1^a, a plunger comprising side arms, 2, 2, cross-heads, 2^a, and a stem, 2^b, which houses a retracting spring, 3, and is provided at the upper end with an operating handle, 2^c. The cross-head, 1^a, of the stem has a boss, 1^b, constituting a guide bearing for the stem, 2^b, of the plunger, and seating

a stop pin, 4, for the lower end of the spring, 3, the stem, 2^b, being slotted at 2^d, to accommodate the pin in the stroke of the plunger. In the lower ends of the plunger arms, 2, there is journaled a shaft, 5, for a rotor stamp carrier, 6, which is mounted on said shaft, 5, rigid therewith between the two arms, 2, 2, of the plunger; and said shaft is extended beyond said arms forming trunnions, 5^a, 5^b, to afford guidance for the plunger in the standard, being extended out through the said standards which are vertically slotted as seen at 1^d for that purpose. The ink pad carrier comprises the side arms, 7, 7, connected by the cross-bar, 7^a. Said ink pad carrier is hung upon the shaft, 5, for pivotal action thereabout, having limited means of lost motion vertically with respect thereto by means of the elongation of the apertures, 7^b, 7^c, by which it is thus pivotally hung on the shaft. The ink pad carrier is controlled in its position and movement by links 8, 8, which are pivoted at their upper outer ends upon arms, 1^e, projecting rigidly rearward from the standards, 1, 1, respectively at a position in the height of said standards for locating the said pivotal connection of the links somewhat above the level of the shaft, 5, at highest position so that said links trend 85 downwardly and forwardly for their engagement with the side arms, 7, 7, of the ink pad carrier. Said engagement is effected by means of studs, 8^b, projecting from the links, 8, respectively and engaging notches, 7^e, in the side arms of the ink pad carrier, and studs, 7^f, projecting inwardly from the sidearms of the ink pad carrier engaging slots, 8^c, in the links respectively. For guiding the ink pad carrier in its vertical movement and for limiting that movement upwardly and preventing side swing at a part of the path of the up-and-down movement, studs, 7^d, are projected from the side arms, 7, engaging slots, 9^a, in stop blocks, 9, which are mounted on the inner sides of the standards, 1. These slots, 9^a, open rearwardly at a certain limit of the downward movement of the studs, 7^d, as seen at 9^b, to permit the ink pad carrier to swing rearwardly at the proper time for clearing the path of the stamp as hereinafter explained. A spring, 10, coiled around the pivot shaft, 8^x, by which both the links, 8, 8, are connected 100 with the standards, 1, 1, respectively, hav-

ing the ends, 10^a, stopped against screws, 8^c, set into the links respectively, and having its middle part which is formed as a loop, 10^b, stopped against the cross bar, 1^a, of the standard, operates to hold the links normally at their upper and inner limit for upholding the ink pad carrier at the position shown in Fig. 5, that is, stopped by the studs, 7^d, reaching the upper end of the 5 guide slots, 9^a, of the stop plates, 9, the same engagement,—that is, of the studs in the slots mentioned,—serving to limit the inward swing of the ink pad carrier; and the slots, 8^e, in the links, 8, and the notches, 7^e, 10 in the side arm, 7, of the ink pad carrier are positioned and dimensioned so that the studs, 7^f and 8^b, respectively, are stopped at the ends of the slots and notches respectively, in the same position of the parts at 15 20 which the ink pad carrier is stopped with respect to the standard by the engagement of the studs, 7^d, in the slots, 9^a.

The stamp carrier, 6, is a rotor mounted upon the shaft, 5, for rotation thereabout, 25 said rotor having a multiplicity of paraxial seats or faces adapted each for carrying a stamp, so that when the stamps are thus mounted upon the rotor, the rotor has a multiplicity of paraxial printing faces. 30 The means hereinafter described serve to lock the rotor with any selected printing face, or seat for printing the stamp, at the lower side,—that is, positioned to be advanced or pressed downward by the plunger 35 for printing. In this operation, the mechanism thus far described operates for inking the stamp, withdrawing the inking pad from the stamp and clearing the path of the stamp for printing, unaffected by the fact 40 that the stamp carrier has a multiplicity of faces; that is, this mechanism operates precisely as if it were but a single printing face or stamp. The operation of the part thus far described is as follows:

45 At the initial position or position of rest, the plunger is upheld by the spring, 3, upholding the stamp carrier; the ink pad carrier is upheld by the spring, 10, operating through the links, 8, being stopped and limited as to its upward position by the studs, 7^d, reaching the upper ends of the slots, 9^a, 50 in the stop blocks, 9. At this position the ink pad, 7^c, is designed to be slightly below position for contact with the printing face 55 of the stamp on the lower side of the stamp carrier. Upon the initial depression of the plunger, the printing face of the stamp moves down into contact with the upper face of the ink pad and becomes inked; and 60 in the further depression of the plunger the ink pad carrier is forced downward by the pressure of the stamp upon the ink pad, further insuring the thorough inking of the stamp while the ink pad carrier moves 65 downward until the studs, 7^d, reach the

point of lateral or rearward escape from the notches in the slots, 9^a, of the blocks, 9. The upper end of the slots, 7^b, in the plunger side arm in that downward movement, nearly but not quite reaches the shaft, 5. 70 In this downward movement of the ink pad carrier, the engagement of its side arms with the links, 8, by means of a stud, 8^b, and 7^f, in the notches and slots, 7^e and 8^e, respectively, causes the links, 8, to be swung 75 downward and outward while said studs travel in said notches and slots, respectively; the studs, 7^d, having reached the rearward outlet, 9^b, from the slots, 9, further depression of the plunger causes the links, 8, to 80 control the movement of the ink pad carrier by the engagement of the studs, 8^b and 7^f, in the notches, 7^e and slots, 8^e, respectively, and swing the ink pad carrier rearwardly. The links, 8, have at their inner 85 or forward ends, cam projections, 8^g, facing upwardly, and the lower ends of the plunger side arms, 2, have coöperating projections, 2^g, which encounter said cam projections, 8^g, at the same point in the action at which the 90 studs, 7^d, reach the rear outlet, 9^b, from the slot, 9^a; and in the rearward swing which the links, 8, are calculated to give to the ink pad carrier as above described, the cam projections, 8^g, and 2^g, coöperating to force the 95 forward ends of the links, 8, and thereby to force the ink pad carrier downward while it is swinging rearward, thus causing it to withdraw obliquely downward and rearward from the face of the stamp, avoiding 100 the dragging or wiping of the ink pad upon the stamp. Continuation of the downward thrust of the plunger carries the ink pad carrier entirely clear of the path of the stamp, as seen in Fig. 6, while the stamp 105 descends to a position for printing, as seen in that figure. Upon the operator's release of the plunger, the spring, 3, returns the parts to their original position, reversing all the movements above described in the reverse of the order described. 110

The rotor stamp carrier, 6, is desirably constructed with sheet metal heads, 6^a, mounted rigidly on the shaft, 5, and further connected together by stamp holder 115 seats, 6^b. For the purpose of receiving the stamp holder seats and securement thereby, each of the heads, 6^a, is made in general polygonal form, being shown ten-sided, (one side being special in form, for the purpose 120 of accommodating a date stamp as herein-after explained), and the sides, 6^c, being separated by notches, 6^d, which have their opposite sides divergent inwardly, or at least with such trend that the two opposite edges 125 of the projection between two consecutive notches are convergent inwardly, making the projection dove-tail in form; and the parts, 6^b, which form the seats for the printing stamps and which tie the two heads to- 130

gether, are made of sheet metal, folded as shown so as to have longitudinal or lateral flanges, 6^a, projecting back or inward, and converging at the angle of convergence of 5 the two sides of the dove-tail projections mentioned, the blanks from which said tie plates or stamp seats are formed, having end portions, 6^b, which are folded back outside the heads, 6^a, respectively, and have 10 their end portions, 6^b, reflexed each through an aperture, 6^c, in the heads, 6^a, and then inside said heads reflexed outwardly against the inner surface thereof, thus forming hooks by which said tie plates or stamp 15 seats are engaged securely with the heads, 6^a. For stiffening the tie plates or stamp seats longitudinally, they may be provided with a longitudinal corrugation, 6^k, projecting inwardly as seen in Fig. 8.

20 Stamp holders, 12, for holding rubber stamps or the like, 13, are formed of sheet metal folded as shown in Fig. 8, to form lateral longitudinally extending double fold flanges, 12^a, and backward or inwardly extending or converging flanges, 12^b, dimensioned to fit outside the dove-tail projection of the head and the connector plates or 25 stamp seats 6^b engaged therewith as described,—that is to say, said dove-tail or 30 inwardly converging flanges of the stamp plate are spaced to engage outside the dove-tail or inwardly converging flanges of the tie plates or seats 6^b, as seen in Fig. 8. It will be seen that the stamp holders, 12, are 35 adapted to be slidingly engaged with the seats or tie plates, 6^b; and are thus readily removable or replaceable for substituting one stamp for another as may be required from time to time.

23 One sector of the rotor stamp carrier is desirably devoted to carrying a dating stamp, and such dating stamp is shown in Figs. 8 and 9, comprising a shaft, 15, having 40 its ends engaged in the two heads and having mounted upon it between stops or 45 spacing collars or sleeves, 15^a, four rotors, 16, 17, 18 and 19, each having twelve printing faces and correspondingly positioning shoulders, laterally formed upon lateral extensions, 16^a, 17^a, 18^a and 19^a. The rotor, 50 16, has upon ten of its faces figures denoting ten consecutive years, the other two faces being blank for convenience. The rotor, 17, has upon ten of its faces numeral 55 figures from 0 to 9 inclusive, the other two faces being blank for convenience. The rotor, 18, has upon three of its faces the numerals, 1, 2 and 3, the remainder being blank for convenience; and the rotor, 19, 60 has upon its twelve faces the proper abbreviations for twelve months of the year. Each of these rotors is accessible, or can be made accessible at either the forward or rear side of the instrument by turning the 65 rotor by the means hereinafter described;

and each of the rotors, 16, 17, 18 and 19, can be adjusted about the shaft, 15, to bring the proper combination for stamping any desired date directly to the front, or what would be the bottom side when the entire 70 rotor, 2, is adjusted to set the dating stamp as a whole at the lower side. For retaining the rotors, 16, 17, 18 and 19, accurately at the position to which they may be thus adjusted, for a given date positioning 75 plungers, 20, 20, 20, 20, are provided, each having a flat end adapted to contact the flat shoulders of the lateral projections, 16^a, 17^a, 18^a and 19^a, these plungers being mounted in a casing, 21, which is secured 80 in the rotor, 6, between the heads, 6^a, by the engagement of tenons, 21^a, at the ends of the casing in suitable apertures formed in the heads, 6^a, as may be clearly understood from Figs. 8 and 9. Springs, 22, around 85 the stems of the plungers, 20, reacting against the head of the casing and against the shoulders, 20^b, of the plungers thrust the plungers against the shoulders, 16^a, 17^a, 18^a and 19^a, thereby bringing the rotors, 90 16, 17, 18 and 19, to accurate position and holding them at that position with sufficient certainty for accurate performance of the work of stamping the date.

95 An important part of this invention consists in the means for adjusting the rotor stamp carrier to bring any desired stamp at printing position, and for indicating what stamp is at printing position without operating the stamp for printing as would be 100 necessary in the absence of any special provision because the stamp is of course concealed by the inking pad and cannot be examined directly. For these purposes the shaft, 5, is provided with a crank handle, 25, 105 at the right hand; and back of said crank handle there is mounted and made rigid with the standard, a notched disk, 26, having in its periphery as many equal-spaced notches as there are stamp-carrying faces on 110 the rotor (including the dating stamp), the crank handle has its radially extending arm or lever double,—that is, comprising a portion 26^a, rigid with the shaft, and a duplicate portion, 26^b, pivoted to the rigid member, 26^a, near the shaft, and provided at its 115 upper end with the operating handle, 27, and with a tooth, 28, for engaging the notches of the disk, 26, that tooth being formed by a projection which is bent inward from the arm, 27^b, and over the end of the arm, 27^a, and extends inward for engagement of the notches, so that it is stopped against the inner side of the arm, 27^a, when it is engaged with the notches, a spring, 29, 120 being provided, tending to hold it in this position and adapted to yield when the knob is pressed inward to disengage the tooth from the notches. By this means, it will be 125 seen that the rotor stamp carrier can be ad- 130

justed to bring any desired face at printing position; and in order to indicate to the operator what stamp is at printing position, there is provided an index segment, 30, having radial arms, 31, by which it is pivoted about the shaft, 5, said segment extending over the forward part of the rotor, and having on its exposed surface index lines or graduations for indexing the several stamps which may be carried by the rotor. Desirably, a movable index card or sheet, 31^a, is provided engaged with flanges, 30^a, on the index segment, which can be removed for noting upon it the title of any particular stamp which may be placed in the rotor, which may be erased and substituted by any other title when another stamp is substituted for the one so indexed. From the cross-bar, 2^a, of the plunger, 2, an index point or reading finger, 2^x is projected to overhang the index segment, and means is provided, now to be described, for rocking the index segment so as to bring into registration with the index finger the particular index line corresponding to the stamp which is at printing position. The means for this purpose comprises a pinion, 35, on the shaft, 5, which meshes with a gear segment, 36, pivoted at 37, on the left hand side arm of the plunger, having a lever arm, 36^a, which extends from the fulcrum oppositely to the segment, provided with a slot, 36^b, which engages a stud, 30^x, projecting from the corresponding side arm of the index segment, the gear segment having within a limited arc the number of teeth of the pinion, 36, and that arc having its fixed radius substantially the distance of the stud, 30^x, from the fulcrum of the segment; so that said segment, 30, will be rocked by the full rotation of the shaft, 5, and the pinion, 35, through an arc about the shaft, 5, sufficient to carry the full number of index lines successively into registration with the index finger. The movement of said index segment being proportional to the rotary step movement of the rotor stamp carrier, the entire ten working positions of the stamp carrier, may be each correctly indicated within the limited arc of the index segment.

We claim:

1. In a self-inking stamp, in combination with a frame and a plunger mounted for reciprocation therein, a rotor carried by the plunger having a multiplicity of paraxially extended faces, each adapted for the mounting thereon of a stamp; means for rotatively adjusting the rotor about its axis on the plunger, and two coöperating elements of an indicator, one having a reading point and the other graduated to be read, one of said elements being fixed with respect to the plunger and the other mounted for oscillation past the first, a pinion on the rotor

and a gear segment of greater radius than 65 the pinion meshing therewith, whereby the full rotation of the pinion rotates the segment only through a limited angle, and means by which the gear segment actuates the oscillating element of the indicator. 70

2. In the construction defined in claim 1 foregoing, the oscillating element of the indicator being mounted for oscillation about the axis of the rotor; a pinion on the rotor co-axial therewith; a gear segment journaled on the plunger with which the pinion meshes, and operating connections between the gear segment and said oscillating element for rocking the latter about the axis of the rotor by the rocking of the segment 80 about a different axis.

3. In the structure defined in claim 1, the graduated element being a segment of a cylinder co-axial with the rotor, extending across in front of the same, and comprising 85 a removable surface sheet having spaced index lines subdividing it according to the step movement of the oscillating element derived from the step movement of the rotor.

4. In the structure defined in claim 1, the graduated element of the index device being the oscillating element thereof, and comprising a segment of a cylinder co-axial with the rotor extending across in front of 95 the same and having its exposed surface subdivided by lines spaced circumferentially of the rotor correspondingly to the step movement of said element derived from the step movement of the rotor in its adjustment for positioning the desired face at 100 printing position.

5. In the structure defined in claim 1, the operating connections between the rotor and the oscillating element of the index device, 105 consisting of a pinion on the rotor, a gear segment with which the pinion meshes, having a lever arm by which it is pivoted on the plunger, a cylindrical segment extending in an arc in front of the rotor having 110 radius arms by which it is pivoted about the rotor axis and a lever arm of the segment arranged to extend alongside one of the radius arms, one of the alongside parts having a slot and the other a stud engaged 115 with the slot for communicating rocking movement to the index segment from the gear segment.

6. In a self-inking stamp, in combination with a supporting frame, a plunger mounted for reciprocation on the frame; a stamp carrier carried by the plunger; an ink pad carrier pivotally carried by the plunger having lost motion connected therewith; an ink pad-controlling link pivoted on the frame at 120 a line offset laterally from the path of reciprocation of the pivotal connection of the ink pad carrier with the plunger, and trending 125

5 downwardly from its said pivot, and having lost motion connection with the ink pad carrier at its lower end; a spring acting on the link to cause it to uphold the ink pad carrier, a guide-way on the frame for the ink pad carrier, the latter having an abutment which engages said guideway in the initial 10 part of the descent of the plunger, the guideway having a lateral opening for the escape of the abutment therefrom at the limit of the lost motion connection of the link to the ink pad carrier, whereby beyond said limit in the descending movement of the plunger, the link controls the ink pad carrier by 15 swinging it laterally about its fulcrum or pivotal connection with the plunger, and co-operating abutments on the plunger and ink pad carrier which coöperate cam-wise for relatively depressing the ink pad carrier 20 with respect to the plunger in the lateral swinging movement of the ink pad carrier.

7. In a self-inking pad, in combination with a frame, a plunger mounted for reciprocation in the frame, a stamp carrier carried by the plunger, an ink pad carrier suspended from the plunger and having lost motion connection therewith permitting relative vertical movement with respect to the plunger; a spring-operated link pivoted to the 25 frame at a line offset laterally from the path of reciprocation of the pivotal connection of the ink pad carrier with the plunger, and trending downwardly from its said pivot, and engaged with the said ink pad carrier 30 for yieldingly upholding the latter, coöperating stops on the frame and the ink pad carrier to limit the uplift of the ink pad carrier by said links, said coöperating stops being adapted also for guiding the ink pad 35 carrier to limit it to a vertical path to a limited distance of descent from the position at which it is stopped by said coöperating stops, the link having lost motion connection with the ink pad carrier for limited movement 40 of the carrier-connected end of the link laterally with respect to the plunger's movement, the several engagements being proportioned for terminating the lost motion between the link and the ink pad carrier, at the same time that the engagement 45 against lateral movement of the ink pad carrier terminates.

8. In the structure defined in claim 7 foregoing, coöperating abutments on the plunger and link for causing the link to be depressed at its end which is engaged with the ink pad carrier, and to depress the ink pad carrier, relatively to the plunger in the

movement of said end of the link laterally with respect to the plunger's movement. 60

9. In a self-inking stamp, in combination with a plunger, a rotor for carrying a multiplicity of stamps, comprising a shaft journaled on the plunger; similar polygonal heads rigid with the shaft, said heads having notches between the consecutive sides of their polygonal outline, the two sides of each notch being inwardly divergent, whereby each side of the polygonal outline is the end 65 of a dove-tail projection, and tie plates connecting the two heads formed for seating on said sides of the polygonal outline, and having flanges which engage the dove-tail projection. 70

10. In a self-inking stamp, in combination with a plunger, a rotor for carrying a multiplicity of stamps, comprising a shaft journaled on the plunger and two similar heads rigid with the shaft, said heads having similar polygonal outline with notches 75 between the consecutive sides of said outline, the opposite sides of each notch being inwardly divergent from each other, whereby the sides of the polygonal outline are the ends of dove-tail projections, and tie plates 80 connecting said heads seated upon the corresponding sides of their peripheral outline, and having inwardly-extending lugs for lapsing outside the heads respectively, said heads having apertures positioned inwardly 85 from the respective sides of their polygonal outline, the ends of said lugs of the tie plate being bent into engagement with said apertures for securing the tie plates in position. 90

11. In a self-inking stamp, in combination with a rotatable stamp carrier comprising a shell consisting of end heads and longitudinally peripherally situated connectors, a stamping device comprising a plurality of rotatable imprinting members; an axle on 100 which they are mounted for rotation, said axle being mounted in the end heads, said imprinting members having laterally positioned polygonal shoulders of less radius than the printing periphery of said members; 105 a casing mounted on and positioned between said end heads, and spring-actuated plungers in said casing having their heads adapted to seat on the faces of the polygonal shoulders of the imprinting members respectively. 110

In testimony whereof, we have hereunto set our hands at Chicago, Illinois, this 28th day of January, 1920.

MAX RUMPF.
WILLIAM E. NIMZ.
